COIL HANDLING MECHANISM

Albert J. Sarka, Maple Heights, Ohio, assignor to Wean Equipment Corporation, Euclid, Ohio, a corporation of Ohio

Application June 25, 1956, Serial No. 593,619

20 Claims. (Cl. 242—79)

This invention relates to coil handling mechanism, particularly mechanism for moving coils into position to be taken by an uncoiler or similar mechanism. My co-pending application Serial No. 593,621, filed of even date herewith, discloses and claims coil handling mechanism which may take the form of an uncoiler, the disclosure also including mechanism for moving coils into position to be taken by the uncoiler. The present application has the same disclosure as said co-pending application but claims the coil handling mechanism for moving the coils into position to be taken by the uncoiler.

The mechanism for moving coils into position to be taken by an uncoiler or other mechanism for taking the coils is believed to be unique in a number of respects, being of extremely simple and inexpensive construction yet effectively and accurately functioning to move coils into the desired position.

I provide, in coil handling mechanism, three coil saddles arranged in side-by-side relation so that a narrow coil may be supported by the middle saddle and a wide coil may be supported by the two outer saddles, means for raising the middle saddle alone to raise a narrow coil supported thereby and means for raising the two outer saddles to raise a wide coil supported thereby.

I further provide, in coil handling mechanism, a coil carrier comprising a body, wheel means carried by the body and adapted to roll upon supporting means when the carrier advances to partially support the carrier and a plurality of coil supporting members arranged in generally parallel generally horizontal relationship each connected at one end to the body and projecting therefrom, and means underlying and supporting the portions of the coil supporting members remote from the body whereby a coil may be introduced between heads portions of which lie between the coil supporting members when the carrier advances.

I further provide, in coil handling mechanism, a coil carrier having a plurality of forwardly projecting coil supporting members arranged in generally parallel generally horizontal relationship with their forward ends freely spaced from one another to enable introduction of a coil between heads portions of which lie between the coil supporting members when the carrier moves forwardly and means underlying and supporting the forward ends of the coil supporting members, said last mentioned means having guiding portions cooperating with the coil supporting members to insure proper guiding as well as supporting thereof. I preferably provide a roll extending generally transversely of the coil supporting members and underlying and supporting the forward ends thereof, the roll having guiding flanges cooperating with the coil supporting members to guide the same when the carrier moves forwardly. Means are preferably provided for driving the roll and the roll may have gear means thereon and rack means may be carried by at least one of the coil supporting members and meshing with the gear means whereby the coil carrier is moved forwardly and rearwardly.

2

I further provide, in coil handling mechanism, a coil carrier, coil positioning means on the carrier, retainers adapted to engage the sides of a coil carried by the carrier and positioned by the coil positioning means and means connecting the retainers to the carrier for relative movement to positions to engage the sides of the coils of different widths. A shaft may be provided on the carrier, the shaft having its axis parallel to the coil axis, and the retainers may be mounted on the shaft for pivotal movement about the axis of the shaft to inoperative positions relatively remote from the coil. The retainers may be mounted on and movable along an elongated mounting member to adjusted positions to engage the sides of coils of different widths. Means may be provided engaging the retainers when in selected operative positions to hold them against movement along the elongated mounting member or shaft.

Other details, objects and advantages of the invention will become apparent as the following description of a present preferred embodiment thereof proceeds.

In the accompanying drawings I have shown a present preferred embodiment of the invention in which

Figure 1 is a side elevational view, with portions in vertical longitudinal cross-section, of a strip uncoiler;

Figure 2 is an end elevational view, with portions in vertical transverse cross-section, of the strip uncoiler shown in Figure 1;

Figure 3 is a plan view of the uncoiler with a portion broken away to show the mechanism at the lower portion thereof;

Figure 4 is a fragmentary vertical cross-sectional view taken on the line IV—IV of Figure 3;

Figure 5 is a fragmentary detail elevational view showing mechanism for moving a coil into place in the uncoiler, a coil being disposed in such mechanism;

Figure 6 is a plan view of the mechanism shown in Figure 5 but with the coil removed; and

Figure 7 is a vertical transverse cross-sectional view taken on the line VII—VII of Figure 5.

The uncoiler comprises a generally horizontal base 2 carrying upward projections 3 at opposite sides thereof. Each upward projection 3 carries a stationary bearing 4 whose axis is horizontal, the bearings 4 in the respective upward projections 3 being coaxial. Mounted for sliding movement in each of the bearings 4 is a hollow shaft 5. Rotatably mounted on the inner end of each of the hollow shafts 5 is a generally upright generally circular member 6 having therein a socket 7, the sockets 7 each being open at one side, the open sides of the sockets facing each other. Each of the members 6 is journaled on a bearing 8 carried by the corresponding hollow shaft 5.

A shaft 9 is coaxial with each hollow shaft 5 and disposed therewithin but projecting therefrom at the inner end thereof. Each shaft 9 is mounted for sliding movement axially of the corresponding hollow shaft 5 upon a bearing 10 carried by the shaft 9 and a bearing 11 carried by the hollow shaft 5 and disposed therewithin. Rotatably mounted upon the extremity of each shaft 9 is a coil supporting member 12. Each coil supporting member 12 has a generally circular rim 13, and a bearing 14 is disposed about the rim 13 and bears against the annular wall of the corresponding socket 7. Each coil supporting member 12 is rotatably mounted on the corresponding shaft 9 by bearings 15. Thus each member 6 may rotate relatively to the corresponding hollow shaft 5 and each coil supporting member 12 may rotate relatively to the corresponding shaft 9, the members 6 and 12 at each side of the uncoiler normally rotating together in operation of the uncoiler. To insure such rotation together keys 15a are built into the socket

In Figure 3 the clutch members 57 and 57b are shown in engagement and the clutch members 58 and 58b are shown out of engagement. In that position of the parts the motor 54 drives the shaft 57a but does not drive the shaft 58a. If the operating handle 64 is moved toward the left viewing Figure 3 the rod 66 is moved toward the right and because of its connection with the lever 59 at 57 turns the lever 59 in the counterclockwise direction about the axis of the pivot 60 to disengage the clutch members 57 and 57b and engage the clutch members 58 and 58b. When that has been done the shaft 58a is driven while the shaft 57a is not driven.

The shaft 57a is connected with the worm 48a to drive the same by a sprocket chain 68. The shaft 58a is connected with the worms 47a and 49a to drive the same by sprocket chains 69 and 70 respectively. Thus when the shaft 57a is driven the saddle 48 alone is operated and when the shaft 58a is driven the saddles 47 and 49 are operated but the saddle 48 is not. The motor 54 is a reversing motor so the shafts 57a and 58a may be driven in both directions. Driving of the motor in one direction raises the saddle or saddles and driving of the motor in the opposite direction lowers the saddle or saddles. When a narrow coil is being handled it is introduced centrally upon the saddle 48 and by that saddle alone raised into coaxial position in the uncoiler. When a wide coil is being handled it is also introduced centrally of the uncoiler but is raised by the saddles 47 and 49, the saddle 48 remaining in its lowered position.

Rotatably mounted in bearings 71 carried by the base 2 is a roll designated generally by reference numeral 72 whose axis is parallel to the common axis of the hollow shafts 5 and the shafts 9 and to the axes of the rollers 35 and which is generally cylindrical but provided at spaced intervals with annular flanges 73. The flanges 73 are spaced apart to provide guideways 74 for elongated coil supporting members presently to be described. The roll 72 is driven by an electric motor 75 through a gear reducer 76, a driving pinion 77 and a driving gear 78 on the end of the roll shaft with which the driving pinion meshes.

It will be noted that there are four of the guideways 74 and that three of them are defined on both sides by flanges 73 alone while one of the guideways is defined on one side by such a flange with a ring gear 79 at its periphery.

I provide a coil carrier comprising a body 80 in which is mounted an axle 81 carrying wheels 82. The wheels 82 are adapted to ride upon rails 83 which extend generally longitudinally of the uncoiler or in other words generally transversely of the axis of the uncoiler which during an uncoiling operation coincides with the axis of the coil being uncoiled. One of the wheels 82 is flanged as shown at 84 to insure guiding of the carrier in its movement along the rails. The coil carrier also has a plurality of elongated coil supporting members 85. The elongated coil supporting members 85 are connected at one end to the body 80 of the carrier and project therefrom in cantilever fashion. There are four elongated coil supporting members 85 in the form of structure shown in the drawings, such members being of uniform width coinciding with the width of the guideways 74 and also having the same spacing as the guideways 74. The respective elongated coil supporting members 85 have their portions disposed relatively remote from the body 80 of the carrier supported upon the roll 72 between the flanges 73 so that in movement of the carrier along the rails 83 the elongated coil supporting members 85 are supported and guided by the roll 72. Desirably the upper surface of the roll 72 intermediate the flanges 73 is at the same elevation above the upper surfaces of the rails 83 as the upper surfaces of the rollers 35 so that when the coil carrier is projected toward the right viewing, for example, Figure 1, the rollers 35 will assist the roll 72 in supporting the members 85. The member 85 which is disposed

next the ring gear 79 has a rack 86 connected therewith at its outer surface and meshing with the ring gear 79.

The coil carrier is adapted to support a coil either upon the two inner elongated coil supporting members 85 if the coil is a relatively narrow one or upon all four of the elongated coil supporting members 85 if the coil is a wider one. Chocks 88 carried by the members 85 at the upper surfaces thereof are adapted to position a coil upon the coil carrier as shown in Figure 5. The spacing 10 apart of the elongated coil supporting members 85 is such that when those members lie in their advanced position so that they are generally above the saddles 47, 48 and 49 they will not interfere with upward movement of the saddles to take and raise upwardly therefrom a coil disposed thereon. As is clearly shown in Figure 2 the saddle 48 operates between the two inner elongated coil supporting members 85, the saddle 47 operates between the outer such member and the next to outer such member at one side of the carrier and the saddle 49 operates between 20 the outer such member and the next to outer such member at the opposite side of the coil carrier. If a relatively narrow coil is being handled it will be introduced upon the two inner elongated coil supporting members 85 and lifted from them by the saddle 48. If a relatively wide 25 coil is being handled it will be introduced upon all four of the elongated coil supporting members 85 and lifted from them by the saddles 47 and 49 operating in unison as above explained. The coil carrier may if desired be retracted after the coil introduced thereon has been lifted 30 therefrom by one or more of the saddles 47, 48 and 49 and while the coil is still supported by the saddle or saddles.

While one coil is being uncoiled another coil may be placed upon the coil carrier, the coil carrier at such time 35 being in its retracted position as shown in Figure 5. The coil may be placed upon the coil carrier by an overhead crane or any other suitable coil handling mechanism. As soon as the uncoiling of the coil which is disposed in the uncoiler has been completed the succeeding coil may be introduced by advancement of the coil carrier until such coil is disposed above at least one of the saddles 47, 48 and 49. Of course, the members 6 and 12 will be positioned out of the way of the incoming coil and also 40 out of the way of the elongated coil supporting members 85. When the coil carrier has reached the inner end of its stroke the coil is raised therefrom and taken by the uncoiler in the manner above described.

The coil carrier has a shaft 89 upon which are mounted two hubs 90. Connected with each hub 90 is a retainer 91. The retainers are to prevent narrow coils from tipping over sidewise. The retainers and hubs may be turned about the axis of the shaft 89 between lowered operative position as shown in Figure 5 and raised inoperative position. When the retainers are in raised inoperative position they may be moved longitudinally of the shaft 89 for adjustment for coils of different widths. Also mounted on the coil carrier is a bar 92 having therein upwardly open slots 93 which receive the retainers 91 as shown in Figures 5 and 6 to maintain them in desired adjusted operative positions. When a narrow coil is set down upon the coil carrier the retainers 91 may be adjusted into positions at the sides of the coil to approximately maintain its orientation as it is introduced into the uncoiler by advance of the coil carrier and prevent it from tipping over. The coil carrier is moved back and forth by operation of the motor 75 in the respective directions, that motor being a reversing type motor.

Subject matter disclosed but not claimed herein is claimed in our copending application Serial No. 593,621 filed of even date herewith.

While we have shown and described a present preferred embodiment of the invention it is to be distinctly understood that the invention is not limited thereto but may be otherwise variously embodied within the scope of the following claims.

I claim:

1. In coil handling mechanism, three coil saddles arranged in side-by-side relation so that a narrow coil may be supported by the middle saddle and a wide coil may be supported by the two outer saddles, means for raising the middle saddle alone to raise a narrow coil supported thereby and means for raising the two outer saddles to raise a wide coil supported thereby.

2. In coil handling mechanism, three coil saddles arranged in side-by-side relation so that a narrow coil may be supported by the middle saddle and a wide coil may be supported by the two outer saddles, raising means connected with each of the three saddles for raising it, a source of power and power transmission mechanism for connecting the source of power selectively with the raising mechanism for the middle saddle and the raising mechanisms for the two outer saddles.

3. In coil handling mechanism, three coil saddles arranged in side-by-side relation so that a narrow coil may be supported by the middle saddle and a wide coil may be supported by the two outer saddles, raising means connected with each of the three saddles for raising it, two drive shafts, one connected with the raising means for the middle saddle and the other connected with the raising means for the two outer saddles, a source of power and clutching means connecting the source of power to one of the drive shafts in one position of the clutching means and connecting the source of power to the other drive shaft in another position of the clutching means so that either the middle saddle alone or the two outer saddles may be raised.

4. In coil handling mechanism, a coil carrier comprising a body, wheel means carried by the body and adapted to roll upon supporting means when the carrier advances to partially support the carrier and a plurality of coil supporting members arranged in generally parallel generally horizontal relationship each connected at one end to the body and projecting therefrom, heads having portions lying between the coil supporting members when the carrier advances and means underlying and supporting the portions of the coil supporting members remote from the body whereby a coil may be introduced between the heads.

5. In coil handling mechanism, a coil carrier comprising a body, wheel means carried by the body and adapted to roll upon supporting means when the carrier advances to partially support the carrier and a plurality of coil supporting members arranged in generally parallel generally horizontal relationship each connected at one end to the body and projecting therefrom, means underlying and supporting the portions of the coil supporting members remote from the body and coil raising means normally positioned below the level of the tops of the coil supporting members and horizontally offset from the coil supporting members so that after the carrier with a coil supported thereon has been advanced to a position with the coil generally above the coil raising means the coil raising means may move upwardly between the coil supporting members and raise the coil therefrom.

6. In coil handling mechanism, a coil carrier comprising a body, wheel means carried by the body and adapted to roll upon supporting means when the carrier advances to partially support the carrier and four coil supporting members arranged in spaced apart generally parallel generally horizontal relationship each connected at one end to the body and projecting therefrom, means underlying and supporting the portions of the coil supporting members remote from the body and three coil raising means normally positioned below the level of the tops of the coil supporting members and horizontally offset from the coil supporting members, one in vertical alignment with each of the three spaces between adjacent coil supporting members so that after the carrier with a coil supported thereon has been advanced to a position with the coil generally above at least one of the coil raising means

such coil raising means may move upwardly between the coil supporting members and raise the coil therefrom.

7. In coil handling mechanism, a coil carrier having a plurality of forwardly projecting coil supporting members arranged in generally parallel generally horizontal relationship with their forward ends freely spaced from one another, heads having portions lying between the coil supporting members when the carrier moves forwardly so that the carrier upon such movement may introduce a coil between the heads and means underlying and supporting the forward ends of the coil supporting members, said last mentioned means having guiding portions cooperating with the coil supporting members to insure proper guiding as well as supporting thereof.

8. In coil handling mechanism, a coil carrier having a plurality of forwardly projecting coil supporting members arranged in generally parallel generally horizontal relationship with their forward ends freely spaced from one another, heads having portions lying between the coil supporting members when the carrier moves forwardly so that the carrier upon such movement may introduce a coil between the heads and a roll extending generally transversely of the coil supporting members and underlying and supporting the forward ends thereof, the roll having guiding flanges cooperating with the coil supporting members to guide the same when the carrier moves forwardly.

9. In coil handling mechanism, a coil carrier comprising a body, wheel means carried by the body and adapted to roll upon supporting means when the carrier moves forwardly and rearwardly to partially support the carrier, coil supporting means arranged generally horizontally connected at one end to the body and projecting therefrom, a roll extending generally transversely of the coil supporting means and underlying and supporting the forward end thereof, means for driving the roll and a driving connection between the roll and the coil supporting means whereby the coil carrier is moved forwardly and rearwardly.

10. In coil handling mechanism, a coil carrier having a plurality of forwardly projecting coil supporting members arranged in generally parallel generally horizontal relationship with their forward ends freely spaced from one another, heads having portions lying between the coil supporting members when the carrier moves forwardly so that the carrier upon such movement may introduce a coil between the heads, a roll extending generally transversely of the coil supporting members and underlying and supporting the forward ends thereof, means for driving the roll, the roll having gear means thereon, and rack means carried by at least one of the coil supporting members and meshing with the gear means whereby the coil carrier is moved forwardly and rearwardly.

11. In coil handling mechanism, a coil carrier having a plurality of forwardly projecting coil supporting members arranged in generally parallel generally horizontal relationship with their forward ends freely spaced from one another, opposed heads adapted to engage a coil at opposite sides thereof axially of the coil, at least one of the heads having a portion adapted when the head is in an operative position to lie between the coil supporting members when the carrier moves forwardly so that a coil carried by the coil supporting members may be introduced into position generally between the heads and means underlying and supporting the forward portions of the coil supporting members.

12. In coil handling mechanism, a coil carrier having a plurality of forwardly projecting coil supporting members arranged in generally parallel generally horizontal relationship with their forward ends freely spaced from one another, opposed heads adapted to engage a coil at opposite sides thereof axially of the coil, at least one of the coil supporting members being disposed between

portions of the heads when the carrier moves forwardly to introduce a coil carried by the coil supporting members into position generally between the heads, means underlying and supporting the forward portions of the coil supporting members and coil raising means normally positioned below the level of the tops of the coil supporting members and horizontally offset from the coil supporting members so that after the carrier with a coil supported on the coil supporting members has been advanced to position the coil generally between the heads the coil raising means may move upwardly between the coil supporting members to raise the coil therefrom to position the coil substantially coaxially with the heads.

13. In coil handling mechanism, a coil carrier having a plurality of forwardly projecting coil supporting members arranged in generally parallel generally horizontal relationship with their forward ends freely spaced from one another, opposed heads adapted to engage a coil at opposite sides thereof axially of the coil, means for relatively moving the opposed heads toward each other to engage a coil and coil raising means horizontally offset from the coil supporting members adapted after the carrier with a coil supported on the coil supporting members has been advanced to position the coil generally between the heads to move upwardly between the coil supporting members to raise the coil therefrom to position the coil substantially coaxially with the heads whereafter the carrier may be retracted while the coil is supported by the coil raising means to permit relative movement of the heads toward each other to engage the coil.

14. In coil handling mechanism, a coil carrier having forwardly projecting coil supporting means arranged generally horizontally in cantilever fashion, opposed heads adapted to engage a coil at opposite sides thereof axially of the coil and disposed with the axis of the heads extending generally transversely of the coil supporting means and anti-friction means underlying the heads and at least partially supporting the heads for rotation, said anti-friction means also being positioned to underlie and support the cantilevered portion of the coil supporting means when the carrier has been advanced to position a coil generally between the heads.

15. In coil handling mechanism, a coil carrier having forwardly projecting coil supporting members arranged in generally parallel generally horizontal relationship with their forward ends freely spaced from one another, opposed heads adapted to engage a coil at opposite sides thereof axially of the coil and disposed with the axis of the heads extending generally transversely of the coil supporting members, spaced apart rollers underlying the heads and at least partially supporting the heads for rotation, said rollers also being positioned to underlie and support the forward portions of the coil supporting members when the carrier has been advanced to position a coil generally between the heads, and coil lifting means disposed intermediate the rollers and intermediate the

coil supporting members to raise the coil from the coil supporting members to position it substantially coaxially with the heads.

16. In coil handling mechanism, a coil carrier, coil positioning means on the carrier, retainers adapted to engage the sides of a coil carried by the carrier and positioned by the coil positioning means and means connecting the retainers to the carrier for relative movement to positions to engage the sides of coils of different widths.
- 10 17. In coil handling mechanism, a coil carrier, coil positioning means on the carrier for positioning a coil with its axis in predetermined orientation, a shaft on the carrier having its axis parallel to the coil axis and retainers mounted on the shaft, the retainers being adapted to engage the sides of a coil carried by the carrier, the retainers being pivotally movable about the axis of the shaft to inoperative positions relatively remote from the coil.
18. In coil handling mechanism, a coil carrier, coil 20 positioning means on the carrier for positioning a coil with its axis in predetermined orientation, an elongated mounting member on the carrier extending generally parallel to the coil axis and retainers mounted on the elongated mounting member and adapted to engage the sides of a coil carried by the carrier, the retainers being movable along the elongated mounting member to positions to engage the sides of coils of different widths.
19. In coil handling mechanism, a coil carrier, coil 30 positioning means on the carrier for positioning a coil with its axis in predetermined orientation, a shaft on the carrier having its axis parallel to the coil axis, retainers mounted on the shaft and adapted to engage the sides of a coil carried by the carrier, the retainers being movable along the shaft to positions to engage the sides of coils of different widths, the retainers also being pivotally movable about the axis of the shaft between operative and inoperative positions, and means engaging the retainers when in selected operative positions to hold them against movement along the shaft.
- 40 20. In coil handling mechanism, a coil carrier having a plurality of forwardly projecting coil supporting members arranged in generally parallel generally horizontal relationship with their forward ends freely spaced from one another, heads having portions lying between the 45 coil supporting members when the carrier moves forwardly so that the carrier upon such movement may introduce a coil between the heads, retainers adapted to engage the sides of a coil carried by the carrier and means connecting the retainers to the carrier for relative movement to positions to engage the sides of coils of different widths.
